CLAIM

The ornamental design for a seal member for semiconductor production apparatus, as shown and described.

DESCRIPTION

FIG. 1 is a perspective view of a seal member for semiconductor production apparatus, showing our new design; FIG. 2 is a front elevation view thereof; FIG. 3 is a rear elevation view thereof; FIG. 4 is a left side elevation view thereof; FIG. 5 is a right side elevation view thereof; FIG. 6 is a top view thereof; FIG. 7 is a bottom view thereof; FIG. 8 is a cross-sectional view thereof; FIG. 9 is an enlarged cross-sectional view of a portion thereof; and, FIG. 10 is an enlarged cross-sectional view of a portion thereof in a condition of use. The broken lines shown in FIG. 10 are for the purposes of illustrating environmental structure and form no part of the claimed design.
